UNITED STATES PATENT OFFICE.

ERNST ANHEUSER, OF RACINE, WISCONSIN.

DETACHABLE TOOL-HANDLE.

1,147,204.

Specification of Letters Patent. Patented July 20, 1915.

Application filed August 4, 1914. Serial No. 854,970.

To all whom it may concern:

Be it known that I, ERNST ANHEUSER, a citizen of the United States, residing at Racine, in the county of Racine and State of Wisconsin, have invented certain new and useful Improvements in Detachable Tool-Handles; and I do hereby declare the following to be a full, clear, and exact description of the invention, such as will enable others skilled in the art to which it appertains to make and use the same.

This invention relates broadly to detachable tool handles and has particular reference to devices of this character which may be readily attached to or removed from files, rasps or other tools of a similar shape which are difficult to grasp and use while also being inconvenient and awkward.

As a principal object this invention contemplates the provision of a tool holder of the character described which shall be readily attachable to or detachable from the rasp, file or other tool by the manual operation of a single adjusting element.

25 A further and coördinate object is to provide a tool holder of this type which shall removably clamp the tool and necessitate the use of no bolts, screws or the like to secure the holder thereto.

30 A still further object is the provision of a two part tool holder, each part being designed to grip a different portion of the tool to be held and provided with its own operating handle, these parts being removably connected by a single adjustable element.

35 As an object of equal importance with the foregoing I also purpose to provide a tool holder of the type above set forth which is constructed with such regard to proportion number and arrangement of parts as to be capable of being cheaply manufactured, which will be durable and efficient in operation and which may be interchangeably used with tools of different sizes.

40 The above and additional objects are accomplished by such means as are illustrated in the accompanying drawings, described in the specification and then more particularly pointed out in the claims which are appended hereto and form a part of this application.

With reference to the drawings, wherein I have illustrated the preferred embodiment of my invention as it is reduced to practice, and throughout the several views of which like characters of reference designate similar parts,

Figure 1 is a side elevation of the holder applied to a surface file or rasp in conjunction with which it is peculiarly adapted for use, Fig. 2 is a sectional view of the matter disclosed in Fig. 1 taken on the plane indicated by the line 2—2 of that figure, Fig. 3 is a similar view taken on the plane denoted 3—3 of Fig. 1, while, Fig. 4 is a detail longitudinal section of an end of one of the gripping members showing the manner of removably holding the adjusting element.

Proceeding now to the description of the drawings the numeral 5 indicates one of the two parts forming my holder proper, the other portion being designated by the numeral 6. The part 5 consists essentially of a base plate 7, an upstanding inclined handle member 8 provided with the reinforcing rib 8' connecting with the base plate and positioned centrally thereon, and the angular retainer extension 9 all of which are formed integral and preferably from some cheap and strong metal, such as cast iron or steel, 80 the handle member 8, it will be noted in this connection, being made hollow for the obvious purposes of lessening the weight and cost of the holder, while not substantially detracting in any way from its strength or 85 durability.

Similarly the portion 6 consists of a base plate 10, the integral upstanding handle member 11, and the boss 12 which when the device is in use as illustrated in Fig. 1 is longitudinally alined with the extension 9 of the part 5, both the boss and the extension being centrally apertured for the reception of the adjusting bolt 13 which is externally screw threaded as at 14 upon one extremity 95 to accommodate the nut 15, the other extremity being provided with the usual head 16 adapted to abut the boss 12.

It will be noted even at a cursory glance at the figure illustrating the complete device 100 that the upstanding handle portions 8 and 11 of the respective parts 5 and 6 present an

appearance similar to the corresponding handle members of the ordinary plane so that one hand of the operator may grasp the inclined member 8 to exert the necessary 5 pushing or pulling force while the fingers of the other hand may grip the knob like member 11 to guide or direct the movement of the tool securing the holder.

Each of the tools adapted for use in conjunction with this invention has preferably 10 the flat upper surface 17 upon which the bases 7 and 10 of the parts 5 and 6 may rest in horizontal as well as longitudinal alignment and has its ends unequally beveled as 15 shown at 18 and 19 in order to be reliably secured in the similarly shaped rounded lips 20 formed at one extremity of each of the base plates 7 and 10 all as clearly illustrated in Fig. 1. As is to be noticed in this 20 figure the tool used is a flat file or rasp 21 which is provided with the usual projections or teeth 22 and which as will be seen has no peculiar construction other than the beveled ends just described and which is so 25 firmly held by the device shown that no bolts or other auxiliary fastening means are necessitated in order to secure a practically integral coöperation between the holder and the tool thus held.

30 With regard to the position and use of the adjusting bolt 13 it will be seen that the angular extension 9 is formed with the integral lip 23 as is best shown in Figs. 3 and 4, this lip being so spaced from the bed 35 plate 7 as to properly accommodate the nut 15 therebetween and to accordingly prevent rotation of the nut when the bolt is being adjusted. To remove the holder from its position shown, the bolt 13 is rotated by a 40 proper pressure applied to the head 16 which quickly withdraws the bolt from the nut 15 allowing the separate parts 5 and 6 to be longitudinally and oppositely slid upon the surface 17 of the tool to remove the contact 45 between the angularly recessed lips 20 and the beveled ends 18 and 19 of the tool so that the two parts of the holder may be lifted therefrom and laid away or reaffixed to another size of rasp or a different tool. 50 The manner of assemblage is of course constituted by a reversal of the steps just described.

An additional means for securely positioning the holder upon the tool and one 55 which prevents all lateral displacement of the former upon the latter is provided by the pairs of lateral lips 24 which as indicated are formed integral with their respective parts of the holder and are adapted to 60 lie against the sides of the tool as indicated in Figs. 2 and 3. These flanges, however, are not actually necessary for the advantageous operation of the improved tool holder and the right is accordingly reserved

to the inventor to either include this means 65 for preventing lateral displacement in future embodiments of his invention, or not, as may seem at the time most expedient.

It is to be particularly noted that no part of the holder extends downwardly upon the 70 tool below the file or rasp teeth or even so far as the level of the teeth which renders the device capable of use on pieces of work wider than the file itself and yet does not in any way, owing to the peculiar construction 75 above set forth, militate against the proper operation of a holder of this character. It would accordingly seem that the objects primarily set out above have been accomplished by the construction just previously 80 described and that accordingly the invention herewith disclosed is possessed of the advantages and desirability obviously accruing from the attainment of such objects. While in the foregoing however, there has thus been illustrated in the drawings and 85 described in the specification such combination and arrangement of elements as constitute the preferred embodiment of this invention in tool holders, it is desired to emphasize the fact that such minor changes 90 may be made in the matter of proportion and degree, in later adaptations of this device as shall not alter the spirit of the invention as defined in the appended claims. 95

What is claimed is:

1. The combination with a tool having beveled ends, of a two part holder, one end of each part having a curved lip, the inner faces of which are provided with beveled portions to engage the beveled ends of the tool, each section having an upstanding handle portion, one of said handles having an opening therethrough, and a hollow boss extending therefrom, the opposite section 100 having an upstanding extension at its inner end on which is formed an integral lip, a bolt extending through said boss and handle and through the upstanding extension, a nut 105 adapted to engage the inner end of said bolt and pass below said integral lip to prevent rotation of the nut, and a head at the outer end of the bolt whereby said bolt may be manually rotated to draw the two parts of the holder toward each other. 110

2. The combination with a tool having unequal beveled ends, of a holder constructed in two parts, one end of each part having a gripping lip provided with unequal beveled portions to engage the beveled portions 120 at the ends of the tool, an upstanding handle on each section of the holder, the forward handle having an opening transversely therethrough and a hollow boss projecting from one side thereof, an upstanding member at the forward end of the opposite section 125 having a laterally extended lip, a bolt extended through said boss and handle and

through the upstanding member, a nut adapted to engage the inner end of the bolt and position below said last mentioned lip, a head at the outer end of the bolt and lips 5 at the edges of said sections to engage and prevent lateral movement of the tool.

In testimony whereof I have signed my

name to this specification in the presence of two subscribing witnesses.

ERNST ANHEUSER.
